UNITED STATES PATENT OFFICE.

CHARLES M. PEACOCK, OF OAK PARK, ILLINOIS.

TIME-CONTROLLED APPARATUS.

Application filed August 29, 1926. Serial No. 58,928.

This invention relates to improvements in time controlled apparatus and consists of the matters hereinafter described and more particularly pointed out in the appended claims.

One of the objects of the present invention is to provide an improved mechanism or apparatus for closing and opening an electrical circuit at certain intervals of time, and one embodying a quick make and break of contacts to produce the "snap" action characteristic of circuit switches, thus eliminating arcing between the contacts and the ultimate burning out thereof.

Another object of the invention is to provide a simple and improved setting means for the apparatus by which contact may be made, maintained and broken at the desired timed intervals.

These objects of the invention as well as others, together with the many advantages thereof, will more fully appear as I proceed with my specification.

In the drawings:

Fig. 1 is a view in front elevation of one form of apparatus embodying my invention.

Fig. 2 is a vertical sectional view as taken on the line 2—2 of Fig. 1.

Fig. 3 is another view in elevation with parts broken away to more fully illustrate the mechanism in the interior of the apparatus.

Fig. 4 is a vertical sectional view as taken on the line 4—4 of Fig. 3 with the casing parts omitted to more clearly illustrate the gearing of the time train.

Figs. 5 and 6 are detail perspective views showing the escapement mechanism embodied in my improved apparatus in two different positions.

Fig. 7 is a view illustrating a contact finger actuating pin used in connection with my improved apparatus.

Referring now in detail to that embodiment of the invention illustrated in the accompanying drawings, 1 indicates the front wall of a support or the like having an opening 2 therein in which a cup-like metallic casing 3 is disposed. Said casing includes an annular wall 4, a rear wall 5, and a front radial flange 6, which terminates in an annular flange 7, the front radial flange engaging the front face of the support adjacent the opening 2 therein. Mounted on the annular flange 7 is a ring 8 of insulating material which includes an inwardly extending radial flange 9 spaced forwardly of the

radial flange 6 of the casing 1. Said ring flange has a plurality of arcuately spaced holes 10 therein and on the rear surface of said ring flange is fixed a metallic ring defining an annular shoulder 11. On the front face of the ring 8 are provided numerals running from 1 to 12 in two series and representing the twenty-four hours of the day and as there are four of such holes 10 for each hour, said holes are spaced arcuate distances apart, representing nominally a time interval of one quarter hour or fifteen minutes each. Embracing the casing 1 is a cover-like member 12 having a rear wall 13 which is spaced from the rear wall of the casing 1, and in the space between said casing walls 5 and 13 is located a clock mechanism 14 of any familiar construction.

To the rear wall 5 of the casing 1 is fixed a forwardly extending sleeve 15 including a front wall 16 and attached to the front wall 16 of said sleeve is the rear wall 17 of a cup-like metallic member 18. Said member includes an annular wall 19 of a diameter less than the annular wall 4 and said annular wall 19 terminates in a radial flange 20 arranged in substantially the plane of the radial flange 6 of the casing. On the front face of the radial flange 20 is mounted a dial 21 having the usual numerals thereon. Said dial is enclosed by a concave glass 22 arranged in a ring 23, and screws 24 pass through said ring, and marginal part of the dial and then into said flange 20 to secure the ring and dial in position.

Mounted on the cup-like member 18 and engaging the rear surface of its radial flange 20 is an insulating ring 25 and fixed on said insulating ring is an annular collector ring 26.

Arranged within the casing 3 is a plurality of arcuately spaced spring contact fingers 27, all of which are made integral with an inturned radial flange 28 spaced forwardly of the rear wall of the casing but insulated therefrom by a ring 29, bolts 30 connecting said parts together. Each spring contact finger is formed at its outer end with a hook 31 adapted to be normally engaged with the shoulder ring 11. Said spring fingers are arranged in radial alignment with the holes 10 in the ring flange 8 and any desired spring finger may be released from hooked engagement with the shoulder ring to spring inwardly by inserting a pin 31^a or the like (see Fig. 7) in the corresponding hole 10,

said spring finger being returned to hooked engagement behind the shoulder ring as for instance by manually moving said spring finger radially outward.

5 The clock mechanism 14 includes a minute hand shaft 32 and another shaft 33. Said mechanism may be of the usual alarm clock type under which circumstances, the shaft 33 will correspond to the alarm shaft. The 10 minute hand shaft is journaled at a point between the ends in a bearing sleeve 34 fixed in the wall 16 of the sleeve 15 and to the front end of said shaft which extends beyond the dial 21 is secured the minute hand 15 35. Journaled on the minute hand shaft adjacent the plane of the dial is the hour hand arbor 36 to the rear end of which is fixed a gear 37. Said gear meshes with a pinion 38 loose on a shaft 39 and rotative 20 with said pinion is a gear 40 which meshes with a pinion 41 fixed to the minute hand shaft between the bearing sleeve 34 and arbor 36 upon which the hour hand 42 is fixed. The time train gearing just described is 25 such that the hour hand is turned in timed relation with the minute hand. The shaft 39 before mentioned is journaled in a bearing sleeve 43 fixed in the rear wall 17 of the cup like metallic casing 18 and on the front 30 end thereof is secured a pinion 44 and on the rear end thereof is fixed a second pinion 45. Secured to the ends of the pinion 41 on the minute hand shaft are cam members 46-46, each having diametrically opposite 35 radial shoulders 47-47, the cams being so formed as to include eccentric surfaces which connect the low point of one shoulder with the high point of the other and vice versa. The purpose of these cams will later 40 appear.

Rotatively mounted on the sleeve 15 between the casing walls 5 and 17, respectively, is a second sleeve 48 carrying an escapement wheel 49 of substantially large diameter and 45 which has forty-eight teeth 50, one for every two of the spring contact fingers 27. Fixed to the sleeve 48, one on each side of the escapement wheel are gears 51 and 52, respectively. The gear 52 is driven by a pinion 53 on the shaft 33 while the gear 51 meshes with the pinion 45 fixed on the rear end of the shaft 39. The pinion 44 drives a gear 54 secured to a second arbor 55 journaled on the hour hand arbor 36 and fixed to the 55 arbor 55 is an indicator or hand 56. This hand is associated with a secondary and smaller dial marking 57 on the main dial which markings are numerals running from 1 to 12 in a clockwise direction and corresponding with the numerals on the ring 60 flange 9.

Secured to the rear surface of the escapement wheel 49 which is of a dished cross section is a radial arm 58 set in the same radial 65 plane of the minute hand shaft 32 as the

indicator hand 56. The gearing between the escapement wheel and indicator hand is such that said hand and contact arm rotate in unison and the position of said arm is thus determined by the position of the indicator 70 hand. The outer end of the arm 58 carries a forwardly extending stud 59 which is suitably insulated from said arm and overhangs the plane of the collector ring 26. Said stud 59 carries two contact brushes 60 and 61 respectively in the form of flat spring fingers. The brush 60 has a wiping contact with the collector ring 26 while the brush 61 is spaced a short distance radially inward of the spring contact fingers 27 when said fingers 80 are in their normal inoperative position wherein they are engaged behind the shoulder ring 11. However, when any one or more of said contact fingers 27 are released as before described, they will yield inwardly 85 so as to be engaged by the contact brush 61 in the rotation of the arm 58, as best shown in Fig. 3.

As will be apparent, the pinion 53 on the shaft 33, through the gear 52 tends to rotate 90 the escapement wheel 49 but means are provided to arrest and release said wheel at uniform intervals, thus controlling or governing the intermittent step by step movement of said escapement wheel, which movements 95 are, of course, short, quick or impulsive movements. Associated with said wheel is an anchor 62 (see Figs. 5 and 6) mounted on a rock shaft 63 journaled in casing 5 in any suitable manner. Said anchor includes a 100 lever 64 and two locking pallets 65 and 65^a, respectively, and when the anchor is oscillated the pallets will permit the escape wheel to have an impulsive movement equal to one-half the distance between the teeth on said 105 escapement wheel or in other words an arcuate distance equal to the spacing between the spring contact fingers 27.

The anchor is not vibrated continuously as in a watch or clock, but only at predetermined intervals. Pivoted to the free end of the anchor lever is a depending arm 66 which includes a shoulder 67 and the relative angular position between said lever and arm is determined by a spring 68, fixed at one end to 110 said lever and engaging it at its other end with a fixed part on said arm. A downward movement is imparted to said arm 66 by a lever 69 to oscillate the anchor in one direction, after which the arm is released from said lever as will presently appear and will be oscillated in the other direction by a spring 70 connecting the pallet arm 65^a of the anchor with a fixed part of the casing. The lever 69 has a shaft 70^a at one end by 115 means of which it is suitably journaled in the casing and the other end of said lever has a lateral extension 71 which extends into the plane of the arm 66 to engage the shoulder 67 thereon. A spring 72 (see Fig. 125

5) fixed at one end to said lever 69 and at its other end to a fixed part of the casing imparts a normally downward movement to said lever which is resisted by a detent arm 73 with which said lever engages. The detent arm carries a detent 74 at one end adapted to ride upon the periphery of one of the cams 46 and will impart a slow upward swing to the lever 69 and then permit a quick downward swing thereof (under the action of the spring 72) in accordance with the shape of the cam 46. The detent arm is pivoted at its opposite end on an arm 75 which latter arm is journalled on the bearing 34 and said arm 75 includes an arcuate part 76 with a forward extension 77 at its free end which terminates short of the dial 21 and in line with a short arcuate slot 21^a therein, preferably on the left hand side of the vertical median plane of said dial. By a suitable means inserted through said slot and engaged with the extension 77 the same may be moved to set the detent with reference to the position of one of the shoulders 47 of the associated cam 46. When one of the shoulders of the cam approaches and reaches the detent, said detent slips off the said cam and the spring 72 actuates the lever 69 and through the arm 66 to oscillate the anchor in one direction and permit the escape wheel to receive one impulse or step by step movement, this position of the parts being best shown in Fig. 5. Of course, in the impulse movement of said escapement wheel, a like movement is imparted to the brush arm 58 and brushes carried thereby. At the predetermined time, the arm 66 is released from engagement with the lever extension 71 and is oscillated in the other direction to permit the escapement wheel to receive another impulse and the means for releasing said arm 66 is as follows: 80 indicates a lever which has a rock shaft 81 at one end pivoted in the casing in any suitable manner. The other end of said lever rests upon a detent 82 (see Fig. 3) carried on the free end of a detent arm 83, said detent riding on the periphery of the other cam 46. The said lever is normally held against the detent 82 by a spring 84 (see Fig. 6) and about mid-way between its ends said lever has an extension 85 adapted to engage the arm 66. The detent arm 83 is pivoted at its other end on a setting arm 86 also journalled on the bearing 34. The bearing on which said setting arms 75 and 86 are journalled is threaded into the wall 16 and in this manner said arms are clamped between said wall and a radial flange on said bearing (see Fig. 2) so as to frictionally hold them in the desired angular relation. The member 86 has an arcuate part 87 with a forward extension 88 which terminates short of the dial 21 and in line with an arcuate slot 21^b therein, preferably on the right hand side of the vertical median plane of the dial, the slot 21^b being of a greater length than the slot 21^a. By a suitable means inserted through the slot 21^b and engaged with the extension 88 the same may be moved to set the associated detent 82 with reference to one of the shoulders 47 of the associated cam 46. When said shoulder approaches the detent, said detent moves inwardly and removes its supporting engagement from the lever 80 which under the action of its spring 84 will swing counter clockwise. In this movement the lever part 85 will impinge against the arm 66 and swing it away from the member 71 of the lever 69, when the spring 70 acts to oscillate the anchor 67 in the other direction so that the escapement wheel receives another impulse. In the further rotation of the cams, the lever 69 is again swung upward until the portion 71 thereof again engages the shoulder 67 of the arm 66 ready for the next operation thereof.

I have illustrated the invention as being used to open and close an electric circuit provided by the conductors 90 and 91 respectively, one connected to one of the bolts 30 (and of course to all the contact fingers 27) and the other one connected to the collector ring 26.

If it is desired to close the circuit at 1 p. m. and to hold it closed for fifteen minutes, the pin 31^a is inserted in that hole 10 associated with "one o'clock". If it is desired to close the circuit for one and one quarter hours beginning at 1 p. m., pins 31^a are inserted in the hole 10 associated with "one o'clock" and also in the hole 10 associated with "two fifteen o'clock" and all intermediate holes.

If it is desired to close the circuit before the "hour" and "half hour", this may be done by moving the indicator 77 in the slot 21^a counter-clockwise. For example if it is desired to close the circuit at 12:59 p. m. the pin 31^a would be inserted in the hole 10 associated with "one o'clock" and the extension 77 moved in the slot 21^a counter-clockwise an amount equal to one minute on the dial. This closes the circuit one minute before "one o'clock" and opens it fifteen minutes thereafter. By moving the extension 77 in the slot 21^a it is possible to set the switch to close the circuit up to ten minutes before the hour or half hour. If it is desired to close the circuit for a shorter interval than fifteen minutes, the member 88 is moved counter-clockwise in the slot 21^b. For example if it is desired to close the circuit at 1:00 p. m. and hold it closed for one minute, the member 88 would be advanced in said slot an amount equaling the minute on the dial and this can be done at either hour or half-hour intervals. However, due to the construction mentioned there

are certain periods of five minutes in every hour and half-hour in which action cannot be started but they are not of importance and need not therefore be further mentioned.

Should the clock mechanism stop, the brush 61 may be reset with reference to the hands of the clock by manipulating escapement anchor in any convenient manner.

While in describing my invention, I have referred to certain details of construction as well as form and arrangement of parts, the same is for purpose of illustration only so that I do not wish to be limited thereto except as may be pointed out in the appended claims.

I claim as my invention:

1. An apparatus of the kind described embodying therein, a step by step rotary member, a contact member carried thereby, means providing a plurality of annularly arranged yieldable contact fingers concentric with said step by step rotary member, means for normally holding said fingers in an inoperative position with respect to said contact member, means for releasing desired fingers so that they will yield inwardly to an operative position to be engaged by said contact member, means normally acting to continuously rotate said rotary member in one direction, and escapement means translating said movement into a step by step impulse movement of said rotary member from one contact finger to the next adjacent contact finger.
2. An apparatus of the kind described embodying therein, an escapement wheel, means normally acting to rotate the same, a contact member carried thereby, means providing a plurality of annularly arranged yieldable contact fingers concentric with said wheel, means normally holding said contact fingers in an inoperative position with respect to said contact member, means for releasing desired contact fingers so that they will yield inwardly to an operative position to be engaged by said contact member, an anchor member associated with said escapement wheel to alternately yield to and hold said wheel, a constantly rotating shaft, and means connecting said shaft and anchor to actuate the same.
3. An apparatus of the kind described embodying therein, an escapement wheel, means normally acting to rotate the same, a contact member carried thereby, means providing a plurality of annularly arranged yieldable contact fingers concentric with said wheel, means normally holding said contact fingers in an inoperative position with respect to said contact member, means for releasing desired contact fingers so that they will yield inwardly to an operative position to be engaged by said contact member, an anchor member associated with said escapement wheel to alternately yield to and hold

said wheel, a constantly rotating shaft, means between said rotating shaft and anchor to vibrate the same, and devices associated with said last mentioned means to change the time of vibration of said anchor with reference to said constantly rotating shaft.

4. An apparatus of the kind described embodying therein, an escapement wheel, means normally acting to rotate the same, a contact member carried thereby, means providing a plurality of annularly arranged yieldable contact fingers concentric with said wheel, means normally holding said contact fingers in an inoperative position with respect to said contact member, means for releasing desired contact fingers so that they will yield inwardly to an operative position to be engaged by said contact member, an anchor member associated with said escapement wheel to alternately yield to and hold said wheel, a constantly rotating shaft, a cam on said shaft, means between said cam and said anchor to vibrate the same and means for causing a relative angular movement between said cam and last mentioned means to change the time of vibration of said anchor with reference to said constantly rotating shaft.

5. An apparatus of the kind described embodying therein, an escapement wheel, means normally acting to rotate the same, a contact member carried thereby, means providing a plurality of annularly arranged yieldable contact fingers concentric with said wheel, means normally holding said contact fingers in an inoperative position with respect to said contact member, means for releasing desired contact fingers so that they will yield inwardly to an operative position to be engaged by said contact member, an anchor member associated with said escapement wheel to alternately yield to and hold said wheel, a constantly rotating shaft, a cam on said shaft, a detent riding said cam, a lever operated by said detent to actuate said anchor and means for changing the angular position of said detent on said cam with reference to said shaft.

6. An apparatus of the kind described embodying therein an escapement wheel, means normally acting to rotate the same, a contact member carried thereby, means providing a plurality of annularly arranged yieldable contact fingers concentric with said wheel, means normally holding said contact fingers in an inoperative position with respect to said contact member, means for releasing desired contact fingers so that they will yield inwardly to an operative position to be engaged by said contact member, an anchor member associated with said escapement wheel to alternately yield to and hold said wheel, a constantly rotating shaft, cam members fixed thereto, a detent riding each

cam, a lever actuated by one detent to vibrate said anchor in one direction, a second lever actuated by the other detent to release said first mentioned lever from the anchor, and 5 means independent of said levers for vibrating said lever in the other direction.

7. An apparatus of the kind described, a casing, a cup-like member arranged concentric therewith, a sleeve between said casing and member, a clock mechanism mounted on 10 the casing and including a shaft, means in said casing providing a plurality of annularly disposed spring contact fingers, an annular member associated with said fingers

for holding them in an inoperative position, 15 means for releasing desired contact fingers so that they may yield into an operative position, a collector ring on said member, a rotary contact arm carrying brushes for engagement with said contact fingers and collector ring respectively, and means driven by said clock mechanism and controlled by said shaft thereof for imparting step by step impulse movements to said contact arm.

In testimony whereof, I have hereunto set 25 my hand, this 22nd day of August, 1925.

CHARLES M. PEACOCK.
